UNITED STATES PATENT OFFICE.

CHARLES N. JACOBY, OF ROCHESTER, NEW YORK, ASSIGNOR TO RICHARDSON CORPORATION, OF ROCHESTER, NEW YORK, A CORPORATION OF NEW YORK.

APPARATUS FOR CARBONATING BEVERAGES.

1,370,213.

Specification of Letters Patent. Patented Mar. 1, 1921.

Application filed March 10, 1919. Serial No. 281,716.

To all whom it may concern:

Be it known that I, CHARLES N. JACOBY, a citizen of the United States of America, residing in Rochester, in the county of Monroe and State of New York, have invented 5 certain new and useful Improvements in Apparatus for Carbonating Beverages, of which the following is a specification.

My invention relates to a carbonating apparatus of the type adapted for carbonating a beverage consisting of water and syrup, and has for its purpose to provide automatic means for accurately measuring the syrup, so that it is fed to the carbonating apparatus in definite metered quantities.

An instance of the application of the invention is the manufacture of root beer, which is sold to retailers in syrup form. It is the usual practice for the dealer to measure a certain quantity of syrup and a certain quantity of water, and place both of the measured ingredients into a single container, from which the mixture is fed to a carbonating machine, or otherwise to a discharge point, where it is ready for consumption. With my invention it is unnecessary for the dealer to measure off the syrup and water and thus form a mixture, and a great deal of time and trouble is thus eliminated.

It is my purpose to employ a carbonating apparatus and to feed the water and syrup thereto from separate sources of supply. The proportion of syrup to water will be determined automatically by a metering or measuring device incorporated into the carbonating apparatus, and this insures always having a proper mixture, as predetermined by the operator, and as long as the supply of syrup and water continues. The

syrup can be stored in any suitable tank or container, from which it is fed to the carbonating apparatus, and the only requirement as to syrup is that its container be filled at sufficient intervals to maintain a

supply to the carbonating machine. My invention also makes it possible to utilize any city water supply, from which connection can be made directly to the carbonating apparatus, and this would under most circumstances be the most practical way of obtain-

ing the necessary water supply, although obviously a tank or container for the water may be employed, the same as for syrup.

To these and other ends, the invention consists in certain improvements and combinations of parts, all as will hereinafter be more fully described, the novel features being pointed out in the claims at the end of the specification.

Figure 1 is a perspective view of an apparatus, showing the application of my improvements;

Fig. 2 is a diagrammatic plan view of the gearing;

Fig. 3 is a side elevation, partly in section, of the syrup metering device, and

Fig. 4 is a sectional view taken on the line 4—4 of Fig. 3.

The mechanism disclosed, which is merely for illustrative purposes, includes a carbonating apparatus A, which may be of any conventional form having interior mixing devices, a suitable carbonic acid supply, and a discharge pipe B through which the carbonated beverage is forced under pressure to the point of discharge, and I will now proceed with a description of the novel features that have been incorporated in the apparatus of the general character just mentioned.

C designates a water-supplying means consisting of a pipe which may be connected either with a water tank or with a city water supply. Where city water connection is utilized, a pressure regulator D is employed, and thence the water passes through pipe E to the pump, designated generally at F, and by which the water and syrup are forced into the carbonator.

Syrup is fed from a tank or other container by gravity through a pipe G which contains a metering or measuring device designated generally at H. From the metering or measuring device H a pipe I leads to the pipe E already mentioned, where the syrup and water are brought together and fed to the carbonator. In order to properly proportion the supply of water and syrup, the syrup is fed in predetermined and accurately measured amounts, and the pump 100

and syrup metering device are driven at predetermined relative speeds to accomplish this.

The pump F is driven directly from a shaft K which carries a driving gear L, and the latter is operated from a pinion M which is keyed on the shaft of the motor N. The syrup-measuring or metering device H is controlled by a driving gear O which is actuated by a pinion P on the aforesaid shaft K. By varying the relation of the gear and pinion O and P, the relative speeds of the mixture pump and syrup metering device can be changed to secure any proportion of syrup and water that may be desired, and this may depend upon the nature of the beverage and of the syrup from which it is made. In ordinary practice for manufacturing a root beer beverage, the apparatus would be geared to feed one part of syrup to five parts of water, but these particular proportions are not essential to the purpose of the invention.

The syrup may be fed by any suitable device designed to definitely and accurately measure the syrup, and a convenient mechanism for carrying out my purpose is shown in Figs. 1, 3 and 4, in which Q designates a stationary casing or housing adapted to receive an eccentrically-mounted carrier or disk R, the latter being suitably fixed upon the rotating arbor S which carries the aforesaid gear O. The carrier R is cut away to receive oppositely disposed pistons or blades T. The latter engage the inner periphery of the housing, as shown in Fig. 3, and are held apart, in proper relative position, by the intermediate spring U which is seated in recesses provided for the purpose. As the pistons T rotate with the carrier R, the syrup is metered, that is fed in measured amounts intermittently from the upper passage G into the lower passage I, and thence to the pipe E, as already described. A check valve, such as V, may be provided to prevent back pressure into the syrup feeding device.

In the operation of the structure, syrup is fed to the pipe G from any desirable source, and water to the pipe C from any suitable supply, or from the standard water supply of a city, with which the apparatus can be easily connected. The pistons T of the syrup metering device measure and feed syrup into the pipe E in a definite, predetermined proportion to the water, dependent upon the ratio of gearing between the pinion P and gear O. This gear ratio may cause the syrup metering device to operate once while the pump F completes five operations, for instance, thus taking in one part of syrup to every five parts of water. The mixture is then forced into the carbonator, where it is thoroughly mixed and charged

with carbonic acid gas, as usual in this class of apparatus.

The term "syrup metering device," as used throughout this application, is intended to refer to mechanism which permits a predetermined accurately measured portion of syrup to feed under pressure of its own weight or by gravity, as distinguished from a pump that operates to force a fluid under pressure.

While I have disclosed mechanism in which the syrup is fed to the water line, before entering the carbonating apparatus, this particular arrangement is not essential to the primary purpose of the invention, which is to automatically meter the syrup, and this result might also be attained by metering the syrup and permitting it to feed to the carbonating apparatus independently of the water, the mixing of the water and syrup taking place in the carbonating apparatus. Other modifications in the mechanism shown may be adopted without departing from the fundamental principle of the invention, and the following claims are intended to cover any such changes as may come within the scope of the invention as herein defined.

I claim as my invention:—

1. The combination with a carbonating apparatus, of means for metering syrup in definite predetermined quantities, and means for feeding said metered supply of syrup and water to the carbonating apparatus.

2. The combination with a carbonating apparatus, of means for supplying syrup thereto, and a syrup metering device governing the amount of syrup supplied to the carbonating apparatus whereby the syrup is fed in accurately measured amounts.

3. The combination with a carbonating apparatus, of a pump for supplying a mixture of water and syrup thereto, a water supply pipe leading to said pump, a syrup supply pipe leading to the water supply pipe whereby a mixture of water and syrup enters said pump, and a syrup measuring device controlling the supply of syrup and operated in predetermined relationship with said pump so as to mix the water and syrup in definite proportions before it enters the carbonating apparatus.

4. The combination with a carbonating apparatus, of a pump for supplying a mixture of water and syrup thereto, a water supply pipe leading to said pump, a syrup supply pipe leading to the water supply pipe, a syrup measuring device, driving means for the aforesaid pump, and gearing between said driving means and the syrup measuring device whereby the latter is operated once during a series of operations of the pump.

5. The combination with a carbonating

- apparatus, of a pump for supplying a mixture of water and syrup thereto, water conducting means leading to said pump, syrup conducting means leading to the water conducting means, and a syrup metering device controlling the flow of syrup in the syrup conducting means, whereby the syrup is accurately measured in predetermined amounts before becoming mixed with the water.
- 5 6. The combination with a carbonating apparatus, of a pump for supplying a mixture of syrup and water thereto, a water supply pipe leading to said pump, a syrup supply pipe leading to the water supply pipe, a rotary syrup measuring device, driving means for said pump, and gearing between said driving means and the rotary syrup measuring device whereby the latter is operated once during a series of operations of the pump.
- 10 7. The combination with a carbonating apparatus, of a pump for supplying a mixture of syrup and water thereto, a water supply pipe leading downwardly to the water supply pipe whereby the syrup feeds by gravity, a rotary syrup measuring device controlling the downward feed of the syrup, and operating means whereby said syrup measuring device completes one operation during a series of operations of said pump.
- 15 8. The combination with a carbonating apparatus, of a pump for supplying a mixture of water and syrup thereto, a water supply pipe leading to the pump, a syrup supply pipe leading downwardly to the water supply pipe whereby the syrup feeds by gravity, a rotary syrup measuring device
- controlling the downward feed of syrup in the syrup supply pipe, the rotary measuring device including a gear, a driving shaft for said pump, and a pinion on said driving shaft in engagement with said gear of the rotary measuring device.
- 20 9. The combination with a carbonating apparatus adapted to receive a supply of water, of means for supplying syrup to the carbonating apparatus, and a syrup metering device governing the supply of syrup in accurately measured amounts.
- 25 10. The combination with a carbonating apparatus adapted to receive and carbonate water and syrup, of a pump for supplying water to the carbonator, a syrup metering device for feeding the syrup in accurately measured amounts, and operative connections between said metering device and said pump whereby they are driven in fixed relationship.
- 30 11. The combination with a carbonating apparatus, of a pump for supplying syrup and water thereto, water conducting means leading to the pump, syrup conducting means leading to the water conducting means, a syrup metering device located in said syrup conducting means and controlling the flow of syrup therethrough, driving means for said pump, and operative connections between said pump driving means and the syrup metering device, whereby the latter is operated once during a predetermined number of operations of the pump.
- 35 In witness whereof, I have hereunto signed my name.

CHARLES N. JACOBY.
